UNITED STATES PATENT OFFICE.

HENRY J. GAISMAN, OF NEW YORK, N. Y.

CAST-OFF FOR SUSPENDERS.

SPECIFICATION forming part of Letters Patent No. 759,605, dated May 10, 1904.

Application filed February 18, 1904. Serial No. 194,172. (No model.)

To all whom it may concern:

Be it known that I, HENRY J. GAISMAN, a citizen of the United States, residing in New York city, borough of Manhattan, State of New York, have invented certain new and useful Improvements in Cast-Offs for Suspenders, of which the following is a specification.

My invention relates to improvements in the cast-off or connection between suspender-ends and the main straps or webs of the suspenders; and it has for its object to provide a firm support for the suspender-ends from the straps or webs and permit the ready detachment of the suspender-ends.

15 In carrying out my invention I provide a hook that is pivotally supported from the suspender within the flexible cast-off strap and a fastener for holding the hook and strap closed whereby when the hook and strap are 20 opened out the suspender-end will be free to fall away.

The invention also comprises the novel details of improvement that will be more fully hereinafter set forth and then pointed out in 25 the claims.

Reference is to be had to the accompanying drawings, forming part hereof, wherein—

Figure 1 is a face view of a portion of a suspender provided with my improvements.

30 Fig. 2 is a side view thereof. Fig. 3 is a vertical section, the cast-off being shown closed; and Fig. 4 is a perspective view of my improvements.

Similar numerals of reference indicate corresponding parts in the several views.

In the drawings the numeral 1 indicates a portion of a strap or web of a pair of suspenders, and 2 indicates the suspender-ends, all of which may be of any well-known construction.

40 The cast-off is indicated generally at 3 and in the form shown has a short strap or member 4, of leather or other suitable flexible material, shown as having one part, 4^a, passing through a ring or loop 6, connected with the suspender-web.

45 At 7 is indicated a hanger, shown having one end bent in hook form at 7^a and passing through the eye of the ring or loop 6, so as to 50 be hung therefrom, and the free end 4^b of the

strap 4 is shown secured between the members of the hanger 7 at the hooked end 7^a and riveted thereto, as at 8. By this means both the strap and the hanger are conveniently secured together and suspended from the loop 6, and as the strap 4 passes from the hanger 7 up through the loop 6 and then down below the bight in the strap at 4^c assists in sustaining the weight on the strap.

At 9 is indicated a metal hook, which is 60 preferably relatively long at its bent portion 9^a, and said hook is shown pivotally supported from the hanger 7, as at 10, and is adapted to lie within the lower bight or loop formed by the strap 4, as at 4^d, when the strap is 65 folded up, and said hook is shown attached to the free end of the strap 4, as by a rivet or other fastener, as at 11. The hook 9 when folded upwardly, as in Fig. 3, receives the bight of the suspender-end 2 and is then fastened to the hanger 7 by means which permit the ready detachment of the hook from said hanger. As shown in the drawings, the free end of the hook 9 is coiled or bent, as at 9^b, 70 in spring-loop form and adapted to pass into 75 an opening or socket 7^b in the hanger 7, which opening is of such proportion relatively to the coil 9^b as to provide a spring-like gripping action in said opening, the coil 9^b passing partly through the opening 7^b and forming a 80 tight fit therein. The tip end 4^e of the strap 4 is shown extending beyond the rivet 11 in position to be grasped by the fingers for swinging the hook 9 upon its pivot.

When it is desired to cast off the suspender-end, the free end of the strap 4 is drawn outwardly and the part 9^b of hook 9 is withdrawn from the opening 7^b of the hanger 7 and then the hook swings or turns outwardly, so that the bend 9^a of the hook passes sidewise to permit the ready discharge of the suspender-end, and when the cast-off is to be fastened or closed the hook 9 guides the fastener member 9^b into aperture 7^b. When the cast-off is closed and the suspender-end is in position, as 95 in Fig. 3, the strain and wear are assumed by the hook and hanger and the strap or loop 4 is relieved from such wear; but the strap conceals the hook and hanger and keeps the same from producing wear on the clothing and at 100

the same time serves as a convenient means for manipulating the hook.

Modifications may be made in the details of construction shown and described without departing from the spirit of my invention.

Having now described my invention, what I claim is—

1. A suspender cast-off comprising a strap, a hanger, a hook pivotally connected therewith and lying within the bight of the strap when the latter is folded and having its free end connected with the strap, and means for holding the hook and strap closed, substantially as described.
2. A suspender cast-off comprising a strap, a hook pivotally supported and adapted to lie within a bight of the strap when the latter is folded, said hook being connected with the free end of the strap, and means for holding the hook in an upwardly-turned position to support a suspender-end, substantially as described.
3. A suspender cast-off comprising a strap, a hanger, a hook pivotally connected therewith and lying within the bight of the strap when the latter is folded and having its free end connected with the strap, the hook and hanger being provided with fastener members for causing the hook to be held firmly in an upturned position, substantially as described.
4. In a suspender cast-off a hanger adapted to be hung from a suspender-web, a hook pivotally connected with said hanger adapted to fold upwardly to receive a suspender-end, and means provided on the hook and the hanger to coact in holding the hook in an upturned position, substantially as described.
5. In a suspender cast-off a hanger adapted to be hung from a suspender-web, a hook pivotally connected with said hanger adapted to fold upwardly to receive a suspender-end, one of said parts having a projection and the other part having an opening or socket to receive the projection for holding the hook in an upturned position, substantially as described.
6. In a suspender cast-off a hanger adapted to be hung from a suspender-web, a hook pivotally connected with said hanger adapted to fold upwardly to receive a suspender-end, said hanger having an opening or socket and the hook having a bent portion adapted to fit snugly in the opening or socket to hold the hook in an upturned position, substantially as described.
7. A suspender cast-off comprising a hanger adapted to be hung from a suspender-web, a strap connected with said hanger and arranged

to fold around the same, a hook pivotally connected with the hanger arranged to lie in the bight of the strap, the hook being connected with the free end portion of the strap, and means for holding the hook in an upturned position, substantially as described.

8. A suspender cast-off comprising a hanger adapted to be hung from a suspender-web, a strap connected with said hanger and arranged to fold around the same, a hook pivotally connected with the hanger arranged to lie in the bight of the strap, the hook being connected with the free end portion of the strap, the hook having a projection and the hanger having an opening or socket to receive said projection for holding the hook in an upturned position, substantially as described.

9. The combination of a loop, a hanger having a bent end portion hung on said loop, a strap having an end secured between the members of the bent part of the hanger and passing through said loop, the free end of the strap being arranged to fold upwardly around the hanger, a hook pivotally connected with the hanger and secured to the free portion of the strap so as to lie within the bight of the strap, and means for holding the hook firmly in an upturned position, substantially as described.

10. The combination with a suspender-web, of a cast-off strap connected at one end with the web and having its other end adapted to depend and be folded upwardly to receive a suspender-end, a hook lying on the inner face of the strap, secured to the free end of the latter, and arranged to have the bent portion turned within the bight of the strap when the latter is closed, and means for holding the hook closed with its free end in an upturned position, substantially as described.

11. A suspender cast-off comprising a strap adapted to be folded, a support for a suspender-end located within the folded portion of the strap, said support being hinged within the folded portion of the strap, and means for keeping the strap and support closed, substantially as described.

12. A suspender cast-off comprising a strap adapted to be folded, a suspender-end support comprising two parts pivotally connected together and located within the folded portion of the strap, and means for firmly holding the strap and support in position to retain the suspender-end, substantially as described.

HENRY J. GAISMAN.
